HIGH-FREQUENCY TUBE STRUCTURE

Arthur E. Harrison, Princeton, N. J., assignor to
The Sperry Corporation, a corporation of Delaware

Original application January 29, 1942, Serial No.
428,682. Divided and this application Decem-
ber 14, 1946, Serial No. 716,320

8 Claims.

(Cl. 315—5)

1

The present invention relates generally to ultra-high-frequency tube structure and more particularly to improvements in ultra-high-frequency devices of the reflected electron beam type such as disclosed in Fig. 2 of Varian Patent No. 2,250,511 granted July 29, 1941. The present invention is a division of application Serial No. 428,682 filed January 29, 1942, and which issued as U. S. Patent No. 2,414,785, dated January 21, 1947.

Electron discharge devices utilizing a cavity resonator, through which an electron stream is projected for velocity modulation and thereafter is reprojected under the influence of a reflecting electrode structure to sustain oscillations within the resonator, are now generally termed "reflex klystrons." A principal object of the present invention is to provide improvements in velocity-modulated tubes, especially of the reflex klystron type, for providing focusing of the reflected electron beam and therefore improving the operating efficiency.

Another object of the present invention is to provide means in a reflex klystron for focusing the returned or reflected electron beam, as by an electrode disposed between the resonator and the reflector electrode.

A further object of the present invention is to provide improved resonator constructions for ultra-high-frequency tubes permitting satisfactory operation over wider frequency ranges.

Other objects and advantages of the present invention will become apparent from the specification taken in connection with the accompanying drawings, wherein the invention is embodied in concrete form.

Fig. 1 is a partial cross-sectional elevational view of a preferred form of tube according to the present invention;

Fig. 2 is a similar view taken at right angles to that of Fig. 1;

Fig. 3 is a cross-sectional view of the devices of Figs. 1 and 2 along line 3—3 thereof.

Referring to the drawings, a resonant chamber or cavity resonator 92 is provided in the form of a round conducting disc 93 which is turned or otherwise suitably formed into a substantially cylindrical cavity, having an end wall 94 which is centrally apertured and carries an exit grid 95, where such grid is used. A flexible conducting diaphragm 96 closes the other end of the resonator 92 and carries a reentrant apertured member having a cylindrical portion 101 and a tapered or frusto-conical portion 97 reentrant into the resonator 92.

2

Reentrant tapered portion 97 carries an entrance grid 98 which, when used, is placed concentric with and close to exit grid 95. As shown in Fig. 3, grids 95 and 98 may consist of radial 5 conducting long and short wires 99 and 100 which may be inserted into wall 94 and reentrant member 97 by placing in milled radial slots in the upper surfaces of members 94 and 97. Thereafter hydraulic pressure applied to these upper surfaces will cause the surface metal to flow over the wires, thus staking them in position. Any other method may be used which will leave relatively smooth surfaces after the grids are inserted.

15 Outside of the resonator 92, reentrant portion 97 may be extended as a tubular portion 101 provided with a flange 102 which cooperates with a similar flange 103 attached to the resonator body 93 to provide any desired tuning mechanism for the resonator, such as that shown in Fig. 1 of the above-mentioned parent application, for example.

20 A cathode 104 is provided having its emitting surface placed close to entrance grid 98 and well inside of tubular portion 101. This cathode 104 25 may be similar to that illustrated in Figs. 9-11 or 14 of the parent application, and may be surrounded by a tubular focusing shield 105 extended past emitter 104 toward the entrance grid 98 and supplied with a voltage relative to cathode 104 sufficient to give slight convergence to the resultant electron beam. Focusing shield 105 is supported from and supplied with proper voltage by leads 106 passing through a glass press or seal 107.

25 A reflector plate is provided in the form of a flat disc 130 supported from an upper glass bell or press 21 by a lead-in strut 82. Reflector disc 130 is surrounded by a concentrically positioned focusing ring 131 supported from lead-in struts 121. Ring 131 imparts a slight focusing effect to the electrons on their return trip toward exit grid 95, so that fewer returning electrons strike the outside resonator wall 94 and more electrons 30 re-enter resonator 92 to yield useful energy thereto.

35 Reflector disc 130 is preferably operated at or near the potential of cathode 104, and focusing ring 131 may be slightly positive or negative with respect to disc 130.

An output coaxial line terminal 111 through 40 which ultra-high-frequency energy may be removed from resonator 92 is shown coupled thereto by a coupling loop 109. It will be understood that a glass seal 113 between the inner conductor 110 and the outer conductor 112 of terminal 111 45 is provided for maintaining the internal vacuum.

It is evident that any desired number of such coupling loops and concentric line terminals may be provided.

When using very short wavelengths, difficulty is often experienced in obtaining a broad tuning range by varying the grid separation, due to the fact that the relatively small resonator sizes consequent upon the short wavelength, prevent large variations in grid spacing. Under these conditions, the construction shown in Figs. 1-3 may advantageously be used. In this figure, two conductive members 129, 129' in the form of axial non-diametric sections of a disc are inserted against resonator walls 94 and 93, leaving a small free space above diaphragm 96 to permit its motion. The resultant elimination of complete axial symmetry in the resonator produces a situation where, for a given resonant frequency, the size of the resonator is enlarged, permitting a larger diaphragm 96 and thereby permitting an extended tuning range.

It will be understood, of course, that the focusing ring 131 need not be used simultaneously with the plugs 129, 129', but may be used even where plugs 129, 129' are omitted, and vice versa.

Since many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What is claimed is:

1. A cavity resonator comprising a conductive cylindrical casing portion forming an enlarged portion of a resonant chamber, body means thereon forming a constricted portion of said resonant chamber, said portions being located adjacent one another forming said resonant chamber, and apertured end walls connected to the outer ends of said casing portion and said body means, one of said end walls being flexible to facilitate the adjustment of the resonant frequency of said resonant chamber.

2. A high frequency tube structure comprising a cavity resonator having a pair of apertured walls, means positioned on one side of and concentric with said apertured walls for passing a stream of electrons through said resonator by way of said apertured walls, means positioned on the other side of and concentric with said apertured walls including a reflector electrode for redirecting said electrons back through said resonator, and means projecting in said resonator for increasing its resonant frequency without changing the outer dimensions of the resonator.

3. A reflex klystron comprising a cavity resonator having an electron permeable region, an electron emitter aligned therewith, a flat disc-shaped reflector electrode aligned with said emitter, said electron emitter and said reflector electrode being positioned on opposite sides of said region, whereby an electron beam traverses said region, and a cylindrical-focusing electrode concentric with and in part surrounding said reflector electrode, said focusing electrode being farther positioned in close proximity to the path of said electron beam.

4. A reflex klystron comprising cavity reso-

nator means having electron-permeable foraminite first and second grids aligned along an axis, means for projecting and reflecting an electron beam only in a dual traverse of said resonator means, said electron projecting and reflecting means including an electron source, said electron source being adjacent said first grid and aligned along said axis, said electron projecting and reflecting means further including a reflector electrode, said reflector electrode being adjacent said second grid and being aligned along said axis, and a focusing electrode aligned along said axis and partially disposed intermediate said reflector electrode and said second grid of said resonator means.

5. Apparatus as in claim 4 further including means in said resonator means for destroying axial symmetry thereof, whereby said resonator means may have a wider tuning range.

20 6. Apparatus as in claim 3 wherein tubular means are provided substantially concentric with and partially surrounding said focusing means, said tubular means defining a portion of the vacuum envelope of the klystron.

25 7. A high frequency tube structure having an axis comprising a conductive casing having a substantially right-circular cylindrical inner surface aligned along said axis, said casing further having end wall means with portions thereof substantially perpendicularly disposed to said axis, said end wall means further having centrally-disposed electron-permeable regions, said surface of said casing and the opposed surfaces of said end wall means forming a chamber, an electron source for providing electrons for projection through said regions, a reflector electrode aligned along said axis for reversing said electrons and redirecting said electrons through said regions, and a conductive block positioned within said chamber out of the path of said electrons and connected to a portion of said chamber, the exposed surfaces of said block and chamber providing a resonator which is asymmetrical with respect to said axis.

45 8. A velocity-modulated generator of the reflex type comprising an electron emissive cathode, a resonant member adjacent thereto having apertured wall portions, a reflector electrode disposed on the opposite side of said resonant member from said cathode, and a focusing electrode concentric with and partly surrounding said reflector electrode.
